UNITED STATES PATENT OFFICE.

THEODORE ABBOTT, OF PHILADELPHIA, PENNSYLVANIA, ASSIGNOR TO
JOHN C. GRAHAM, OF SAME PLACE.

DESIGN FOR A FRINGE PENDANT.

SPECIFICATION forming part of Design No. 15,163, dated July 29, 1884.

Application filed July 23, 1883. Term of patent 14 years.

To all whom it may concern:

Be it known that I, THEODORE ABBOTT, a citizen of the United States, residing in the city and county of Philadelphia and State of Pennsylvania, have invented and produced a new and original Design for the Pendants of Chenille and other Fringes, of which the following is a specification, reference being had to the accompanying drawings, forming part thereof.

The two figures of the drawings represent in front elevation pendants which embody my design. The pendant is in the form of a spirally-fluted spheroid truncated at its extremities, and it is banded or striped in different masses of color divided about its center, the bands or stripes being formed by a silk, worsted, or other suitable covering being of the desired shades.

In the drawings I have shown both of the pendants as banded as to the upper portion in a solid mass of color, and as to the lower portion banded in three different shades in Fig. 1, and in four different shades in Fig. 2. The arrangement may, however, be reversed and the smaller bands placed above, if so de-

sired. The upper portion of the solid band may be of any desired shade, and the lower portion may be composite of several bands of different shades without departing from the 30 essential characteristic of a banded spirally-fluted truncated spheroid, as hereinbefore described.

When banded pendants embodying the above design are connected with a heading 35 and embodied in a fringe, the colors of different bands of adjoining pendants may be successively the same, or may alternate or be otherwise fancifully disposed at will.

Having thus described my invention, I 40 claim—

A design for a fringe-pendant, consisting of a spirally-fluted truncated spheroid, banded as to about one-half its length in a solid mass of color, and as to about the other half of its 45 length with bands of different colors.

In testimony whereof I have hereunto signed my name this 13th day of July, A. D. 1883.

THEODORE ABBOTT.

In presence of—

J. BONSALL TAYLOR,
JOHN JOLLEY, Jr.
